P. TILL.

CROCHET NEEDLE HOLDER AND MAGAZINE.

APPLICATION FILED MAY 7, 1921.

1,420,893.

Patented June 27, 1922.

UNITED STATES PATENT OFFICE.

PETER TILL, OF NEW YORK, N. Y.

CROCHET-NEEDLE HOLDER AND MAGAZINE.

1,420,893.

Specification of Letters Patent. Patented June 27, 1922.

Application filed May 7, 1921. Serial No. 467,747.

To all whom it may concern:

Be it known that I, PETER TILL, a citizen of the United States, residing at New York, in the county and State of New York, have 5 invented certain new and useful Improvements in Crochet-Needle Holders and Magazines, of which the following is a full, clear, and exact specification.

This invention relates to holders for 10 crochet needles and has for its object to provide such a holder having means for interchangeably carrying any one of a series of needles in operative position.

Another object is to provide a holder or 15 handle having a magazine cavity for holding one or more needles of a different type or of a reserve supply. Other objects will appear as the description proceeds.

The invention will be first hereinafter de- 20 scribed in connection with the accompanying drawings, which constitute part of this specification, and then more specifically defined in the claims at the end of the description.

In the accompanying drawings, wherein 25 similar reference characters are used to designate corresponding parts throughout the several views:

Figure 1 is an elevation of a holder constructed substantially in accordance with 30 this invention, showing a crochet needle carried thereby in operative position.

Figure 2 is a central longitudinal section of the device as illustrated in Figure 1 showing 35 a needle of a different type arranged in the magazine cavity in the handle.

Figure 3 is a section on the line 3—3 of Figure 2, and

Figure 4 is a detailed elevation of the socketed plug in the end of the holder for receiving 40 the inner end of the needle when clamped in operative position.

The holder comprises a hollow cylindrical handle 1, preferably made of sheet metal with one end portion formed into screw 45 threads 2 adapted to receive the correspondingly threaded portion 3 of a cap 4, which is also preferably made of sheet metal, as best shown in Figure 2. The other end of the tubular handle 1 is closed by a plug 5 of any 50 suitable material which is preferably secured permanently therein by solder, cement, or other suitable means. Said plug projects beyond the tubular handle 1 and is provided with an annular groove 6 adjacent the end 55 thereof. At the other side of the groove 6 the plug 5 is formed with external screw

threads 7, while beyond said screw threads the extremity of the plug is tapered at 8. An axial socket 9 enters said tapered end 8 and extends partially through the plug. 60

A clamping member 10, preferably of sheet metal, has an internal screw threaded portion 11 adapted to engage the external screw threads 7 on the plug, while the outer end portion of said clamping member is tapered at 12 and extends beyond the end of said plug forming a chamber 13 for holding a plurality of clamping balls 14. The extremity of the tapered portion of the member 10 has an opening 15 similar in size and arranged in axial alignment with the socket 9 in the plug 5 so that when said clamping member 10 is screwed outwardly to enlarge the chamber 13, a crochet needle 16 may be inserted through the opening 15 into the 70 socket 9, after which said clamping member may be screwed on for engaging the balls with an annular groove 17 in the shank of the needle, whereby said needle is clamped rigidly to the holder or handle 1 in position 75 for use. After the clamping member 10 is assembled on the plug 5, the inner edge of the former is turned inward to form a flange 18 arranged in the groove 6 of the plug, whereby said clamping member is retained 80 on the plug but allowed sufficient range of movement for releasing and clamping the balls 14, as is required for changing needles. 85

The interiors of the cylindrical handle 1 and cap 4 constitute a magazine cavity or 90 chamber 19 in which one or more needles may be carried when not in use. One such needle 20 is shown in Figure 2, but it will be understood that several others may be accommodated with it in the magazine. The 95 needle 20 is formed with a round nose 21 and sharp hook 22 for use in beading work, whereas the needle 16 has a sharp nose 23 and blunt hook 24 for use in ordinary crocheting. It will thus be seen that with the 100 magazine holder herein shown and described different styles may be interchangeably used, and that needles not in use at a particular time may be conveniently carried in the magazine where they will be always at hand 105 when needed.

I claim:

1. A needle holder having a hollow tubular body of sheet metal open at one end, a cap to fit over said open end of the body for 110 retaining needles within the same, an axially socketed plug closing the other end of the

tubular body, a clamping member of sheet metal adjustable on said plug and having its outer surface flush with that of said tubular body, and needle clamping means carried by said clamping member.

2. A needle holder having a hollow tubular body of sheet metal open at one end, a cap to fit over said open end for retaining needles within said tubular body, an axially socketed plug closing the other end of the tubular body and having external screw threads and an annular groove in its outer

surface adjacent said screw threads, a clamping member of sheet metal adjustable on the screw threads of said plug and having its outer surface flush with that of said tubular body, said clamping member also having an inwardly turned flange at its inner end extending into said groove for the purpose specified, and needle clamping means carried by said clamping member.

In testimony whereof I have signed my name to this specification.

PETER TILL.
